DESIGN FOR A SHOE SOLE

William E. Kavenagh and Clarence L. White,
Windsor, Vt., assignors to Wingfoot Corporation,
Wilmington, Del., a corporation of Delaware

Application November 28, 1940, Serial No. 96,908

Term of patent 14 years

To all whom it may concern:

Be it known that we, William E. Kavenagh and Clarence L. White, citizens of the United States, residing, respectively, at 38 Ascutney Street, and 17 Union Street, in the city of Windsor, in the county of Windsor, State of Vermont, have invented a new, original, and ornamental Design for a Shoe Sole, of which the following is a specification, reference being had to the accompanying drawing, forming part thereof.

We claim:

The ornamental design for a shoe sole, as shown.

WILLIAM E. KAVENAGH.
CLARENCE L. WHITE.
